Geo. Perrey,

INVENTOR.

INVENTOR.
David Pickerman

United States Patent Office.

DAVID PICKMAN, OF LOWELL, MASSACHUSETTS, ASSIGNOR TO HIMSELF AND STUART BISHOP, OF SAME PLACE.

Letters Patent No. 98,188, dated December 21, 1869.

IMPROVEMENT IN SHUTTLE-CHECK FOR LOOMS.

The Schedule referred to in these Letters Patent and making part of the same.

To all whom it may concern:

Be it known that I, DAVID PICKMAN, of Lowell, in the county of Middlesex, and State of Massachusetts, have invented new and useful Improvements in Shuttle-Binders for Looms; and I do hereby declare that the following is a full and exact description thereof, reference being had to the accompanying drawings, and to the letters of reference marked thereon.

My invention consists in a combination of devices with the shuttle-box, operating and disconnected from the protector, whereby the shuttle is stopped and held firm, at a given point, by its end, with but little damage to the picker; and, when operated upon by the picker, guides the shuttle straight through the warp.

To enable others skilled in the art to make and use my invention, I will proceed to describe its construction and operation.

Figure 1 represents a plan of a shuttle-box, with my improved devices.

Figure 2 represents a side elevation, and

Figures 3 and 4 represent a plan, and end view of the block.

Similar letters in the different figures indicate corresponding parts.

a represents a shuttle-box, now commonly used, and located on each end of the lathe, said box being provided with a back-board, *b*, and protector *c*.

Through the bottom of this box, and extending lengthwise of the same, is a mortise, for the reception of the picker *d*, which is operated in the usual manner.

Secured to the back-board *b* is the block *e*, its working-surface being tapering, and concaved or shaped the reverse from the end of the shuttle, as shown in figs. 3 and 4.

On the other side of this box *a* is secured an elliptical spring, *f*. Said spring and block *e* are so arranged as to be adjustable, if required.

The operation of my improved device is as follows:

The shuttle *g* starts, and is stopped at a given fixed point, it being operated in the usual manner, said point being determined and fixed by means of the

block *e* and spring *f*, between which the end of the shuttle *g* passes and stops, which prevents the tip from coming in contact with the picker *d* only at such times as the shuttle *g* is thrown.

This operation not only stops the shuttle, but holds the same at the desired fixed point, until it is required to be operated upon again, which prevents the filling from being thrown off of the bobbin, as there is no abrupt stopping, and consequently, no rebound.

Another important feature is that the shuttle *g*, being stopped before the tip comes in contact with the picker *d*, protects the same, and also, as the speed of the loom varies, the picker *d*, in all cases, meets the shuttle *g* at the same point, while, in the common arrangement, it meets the shuttle at different points, thus preventing it from being thrown as desired.

The shuttle *g* being held firmly at the end, instead of being bound at the middle, prevents the filling from being cut or broken, and with the assistance of the block *e*, the picker *d* giving it the blow in that position, is guided straight across the loom.

Also, the binder-device and the protector *c* being disconnected, the protector *c* may be altered to any required position without interfering in the least with the binder.

And, finally, as the spring *f* and block *e* in their arrangement, tend to release the shuttle *g* rather than to hold it, no extra power is required to throw the shuttle *g*. In the common arrangement of springs, to prevent the rebound, extra power is required.

What I claim as my invention, and desire to secure by Letters Patent, is—

The arrangement within the shuttle-box, and on opposite sides thereof, of the spring *f* and adjustable block *e*, when the said parts are constructed and operate to check the movement of the shuttle, as described.

DAVID PICKMAN.
